UNITED STATES PATENT OFFICE.

EDWARD SEITZ, OF PEORIA, ILLINOIS.

TUCK-MARKING ATTACHMENT FOR SEWING-MACHINES.

SPECIFICATION forming part of Letters Patent No. 425,960, dated April 15, 1890.

Application filed April 14, 1888. Serial No. 270,631. (No model.)

To all whom it may concern:

Be it known that I, EDWARD SEITZ, a resident of Peoria, in the county of Peoria and State of Illinois, have invented certain new and useful Improvements in Tuck Creasers and Markers for Sewing-Machines; and I do hereby declare the following to be a full, clear, and exact description of the invention, such as will enable others skilled in the art to which it pertains to make and use the same.

My invention is in that class of sewing-machine attachments known as "tuckers," and its novel features are hereinafter fully explained, reference being had to the accompanying drawings, wherein—

Figure 1 is a perspective view of the entire attachment, certain portions being broken away to show interior construction. Figs. 2, 20 3, and 4 are enlarged vertical sections at the points *a b c*, respectively, Fig. 1. Fig. 5 is a detail view looking in the direction of the arrow of Fig. 4. Fig. 6 shows the plate *m* enlarged. Fig. 7 shows in perspective the saddle, hereinafter mentioned.

In the drawings, *A* is the presser-bar of a sewing-machine, and *B* is a presser-foot, secured thereto in any suitable manner. Through a heavy block *C*, formed integrally with the foot, passes at right angles to the usual direction of the work a preferably tubular bar *D*, and to this bar all the other parts of the tucker are attached directly or indirectly. Upon the rear lower side this bar is slotted, 35 as indicated in the sectional views, throughout its entire length, for purposes hereinafter explained. The bar slides freely in the block *C*, but is fixed in any desired position with reference to both longitudinal and rotary motion by means of a milled set-screw *E*, working against a saddle *F*, lying within the block *C* and fitting the surface of the bar. A little in front of the bar *D* and parallel thereto is a second bar *H*, grooved upon its 40 lower side nearly its entire length and revolvably mounted at one end in a bearing *I* upon the plate *G* and at the other in a link or arm *X*, rigidly secured to the bar *D*. The horizontal portion of the plate *G* is provided with 45 a scale marked upon its surface and at its left or free end with a rearwardly-projecting por-

tion bearing upon its upper surface a wedge-shaped marking or creasing lug *K*. A little above the plate *G* is a flat bar *J*, having its left end free and its right end secured to the plate. 55 Its free end is provided with a loop *Y*, normally inclosing the lug *K*. Upon the bar *H* is firmly fixed an arm *M*, from which a spring *L* passes forward and downward to rest its grooved lower end upon the lug *K*. A set-screw *N*, 60 working in the arm *M*, serves to increase, if desired, the pressure normally exerted by the spring upon the wedge-lug *K*. By a slight rotation of the bar *H* the spring *L* may be raised from the lug for inserting or adjusting the 65 work. The rotation is effected by means of a sleeve provided with an actuating-lever *P* and with an internal projection engaging the groove in the lower side of the bar. The bar when rotated is held in position at either 70 limit of its motion by a spring *Q*, which passes alternately from the upper to the lower side of the bar *D* when the bar *H* is rotated back and forth.

While the projection entering the groove 75 in the bar *H* prevents rotation of the sleeve upon the bar, it offers no opposition to longitudinal motion of the sleeve with reference to the bar, or vice versa, and as the sleeve is cut away to receive in all portions a lug *R* 80 upon the presser-foot the sleeve and presser-foot maintain the same relative positions when the bars *D H* slide (together, as they must, if at all) back and forth. The bars are thus moved whenever it is desired to vary 85 the distance of the creasing device from the presser-foot.

A gage *S*, formed integrally with a sleeve *T*, sliding upon the bar *D*, serves as a guide for the edge of the work. This sleeve is provided with a set-screw *U*, by which the gage may be fixed at any desired point. The gage is also provided with an adjustable plate *m*, which enters the slot in the bar *D* and prevents the rotation of the sleeve upon the bar. 95 Its edge is serrated to engage the threads of a screw-threaded rod *V*, lying within the bar, whenever such engagement is desirable. When so engaged, rotation of the rod by means of the tips *W* advances the gage along 100 the bar *D* and the locking by the set-screw *U* is unnecessary.

The entire apparatus attached to the presser-foot being supported upon the bar D, it is evident that if the set-screw E be loosened the bar and its attachments may be rotated backward and upward and then secured by the set-screw. In this position it offers no obstruction to ordinary stitching being both above the work and above the visual line to the lower part of the presser-foot.

10. What I claim is—

1. The combination, with a presser-foot, a transverse bar revolvably mounted therein, and means for locking the bar in any of its positions, of tuck-creasing and marking mechanism supported upon the bar alone and otherwise free from the presser-foot, whereby said mechanism may without detachment from the foot be swung upward out of the way when not in use, substantially as set forth.
2. The combination, with the tuck creaser and marker frame and the lower creasing device thereon, of the rocking bar and the lever actuating the same, the upper creasing device borne by the rocking bar, and the curved spring Q, mounted upon the rocking bar, projecting against a convex or protruding portion of the frame, and operating by passing from side to side of such convex portion when the bar is rocked to offer yielding resistance to rocking

the bar from either limit of its rotation, substantially as set forth.

3. The combination, with a transversely-perforated presser-foot, of a slotted tubular bar sliding in said perforation, a tuck-marking mechanism secured to said bar, a threaded rod rotating freely in said tubular bar, and a work-gage sliding upon said bar and provided with a projection passing through the slot therein and engaging said threaded rod, whereby the rotation of the rod forces the gage along the bar, substantially as set forth.

4. The combination, with the presser-foot B, of the transverse bar D, secured thereto, the plate G, rigidly attached to said bar and provided with the creasing-lug K and bar J, the bar H, revolvably mounted parallel to the bar D and bearing the upper creasing device L, screw N, sleeve O, lever P, spring Q, and the sliding work-gage S, adjustably fixed upon the bar D, substantially as and for the purpose set forth.

In testimony whereof I have signed this specification in the presence of two subscribing witnesses.

EDWARD SEITZ.
